John Miller and Andrew Barth
Letters Patent

April 5, 1807 - - -

The Schedule referred to in their Letters Patent and making part of the same containing a description in the words of the said John Miller and Andrew Barth themselves of their machine for making ropes, of any size, as also for spinning Spun-yarn, Log-lines, Fishing-lines, &c.

This machine consists of a box supported by a jack or similar structure, it ships into the windlass of a ship when used on board or into a mortise it is lowered to a post or frame if used on shore. The box is contained a principal ^{wheel} and three spindles. The principal wheel is turned by a crank or wheel fixed on the axis thereof which projects beyond the box on the side opposite to the spindles. The teeth of this wheel are on its edge & may be of such a number proportioned to the teeth on the scutcheon of the spindles as may be deemed proper to give them the requisite velocity. The spindles and scutcheons thereof are three in number inserted in the same box with the principal wheel and having their spindles projecting on the opposite side to that on which the handle is placed. These scutcheons work into the teeth of the principal wheel & are turned by it with any required velocity. The yarn or strands are fastened to the ends of the spindles by holes or hooks and spun together by thereby so laid together for ropes by motion of the machine. The box which forms the frame of this machine is put together by bolts & keys so that it can be easily taken to pieces and removed or stored in a small compass. One or more of the spindles may be used at a time as the more on ship board can be spared to this employment from the other duties on board the vessel.
